METHOD OF ADJUSTING INJECTORS

Harry Amos Johnson, Omaha, Nebr.

Application December 2, 1948, Serial No. 63,039

1 Claim. (Cl. 123—1)

1

This invention relates to a method of adjusting the injectors of a multi-cylinder compression-ignition engine, and to a gage for use in practising said method.

Simply as a convenient way of disclosing the principle of the invention, it will be described as used with a series 71 General Motors diesel engine, which is a typical commercial engine. It is applicable to any engine in which a single master controller actuates a plurality of control racks through individually adjustable connections.

The master controller in this engine is popularly called "the control tube." Mechanically it is a shaft rotatable by an actuating arm through a small angle. It is constructed as a tube to secure good torsional rigidity with respect to weight. Encircling the control tube, and angularly adjustable with reference thereto by means of pairs of opposed tangent screws are control connectors one for each engine cylinder and each connected to the "control rack" for the injector of that cylinder. The term "control rack" is commonly applied to the fuel adjusting element of any fuel injector. In most, but not all, fuel injectors it is literally a toothed rack that engages and turns a pinion on some part, commonly the plunger, of the fuel injector pump, to vary the measured displacement of that pump.

Such pumps are familiar to persons skilled in the diesel engine art and require no detailed description. The problem of adjustment has to do with the positional relation of each control rack relative to the actuator. This is true regardless of the details of construction of the engine. To adjust the specified General Motors engine, the control connectors must be angularly adjusted on the control tube by setting the tangent screws, and a correct setting is one in which all the cylinders receive equal charges of fuel in each of the various positions of the control tube.

The adjustments are made, according to the invention, by freeing all the control connectors. One of said control connectors is adjusted by proper manipulation of the tangent screws. A special direct reading micrometer gage is applied to the actuating arm. The gage readings for certain critical positions of the actuating arm are noted. With the gage still in place, the other injectors are successively adjusted so that the same critical readings are maintained.

The adjustment of the first control connector limits the range of motion of the control tube. By careful observation of the gage, the remaining control connectors may be adjusted, so that

2

each control rack has the same initial critical position, and the same range of motion as were established by adjusting the first control connector.

The best practice is to start by adjusting the control connector nearest to the actuating arm. The reason that this is done is to minimize the error occasioned by possible torsional flexure of the control tube.

The method heretofore used relied on feel. Consequently different mechanics would make different adjustments, and two engines adjusted by different mechanics would seldom run alike. Indeed, few mechanics could adjust all the cylinders of a single engine to secure a strictly uniform distribution of load. The new method gives a clear visual indication of each adjustment, so that a much more uniform standard of performance can be maintained.

A preferred embodiment of my invention is shown in the accompanying drawings in which:

Fig. 1 is a fragmentary perspective view of an engine with the gage in place.

Fig. 2 is a fragmentary front elevation of the engine in which obstructing parts have been broken away showing the gage in place.

Fig. 3 is a detail view, partly in section of an injector control connector and the control tube.

Fig. 4 is a top view of the gage.

Fig. 5 is a side view of the gage partly in section.

Fig. 6 is a section of the gage taken on the line 6—6 of Fig. 5.

Fig. 7 is a section of the gage taken on the line 7—7 of Fig. 5.

Fig. 8 is a detail section of the movable anvil of the gage.

Fig. 9 is a perspective view showing the movable anvil of the gage.

40 The engine's cylinder head is indicated at 1, and injectors are shown at 2. A bearing bracket 3 is mounted on the head 1, and in it the control tube 4 is journaled. There is a similar bearing bracket, not shown, mounted at the other end of the head 1 and supporting the other end of the control tube 4. Mounted on the tube 4 are a plurality of control rack connectors 5. The outer ends of the connectors 5 are linked to respective control racks 6. The control rack connectors 5 are angularly adjustable about the tube 4 and may be moved by loosening the tangent adjusting screw 8 and tightening the tangent adjusting screw 7 and vice-versa. Adjusting screws 7 and 8 engage respective notches 9 and 10 formed in the control tube (see Fig. 3). A

rod 12 leads from the governor 13 to the control tube actuating arm 14. The rod 12 is hinged to the arm 14 by means of a pin 15.

A specially designed gage 16 is mounted between the head 1 and the pin 15 as shown in Fig. 1. The gage 16 comprises a cylindrical body 17. A bracket 18 is fastened to the body 17 by machine screws 19. The bracket 18 is formed with the prongs 21 and 22. Prongs 21 engage the upper horizontal face of the cylinder head and prong 22 engages the inner nearly vertical face. The body 17 has an axial bore 23 in which is slidable the rod 24 which has an enlarged portion 25 which has the same diameter as the bore 23. A cap 26 with opening 27 encircles the rod 15 24 and is fastened to the end of the body 17 by screws 28. A spring 29 biases the rod outwardly of the bore 23. An anvil 29 of channel form is mounted on the outer end of rod 24. The notches 31 provide means for engaging the pin 15 when the gage is in place on the engine. The member 29 is cut away at 30 to permit free passage of rod 12. A bracket 32 is fastened to the body by screws 33. Guided on the bracket 32 is a slide 34 which carries a conventional indicating gage 35 as shown in Fig. 7.

The indicating gage 35 is preferably of the multiplying direct-reading micrometer type. The feeler 36 is connected through a motion multiplying train to the pointer 37. The pointer 37 is arranged so that its axis of rotation coincides with the axis about which the dial 40 may be manually set. This last is a familiar zeroing adjustment. Fastened to the slide 34 is a spacer 38. A set screw 39 is carried by the spacer 38 and engages a recess 41 in the bracket 32.

The control racks are adjusted in the following manner. Number one injector, i. e. the one nearest the actuating arm 14 is ordinarily the first one which is to be adjusted. Preparatory to such adjustment, adjusting screws of all the control rack connectors are loosened and the governor control (not shown) is set in the idle position. Tangent adjusting screw 7 is tightened thus moving the control rack 6 to the right as seen in Fig. 2 toward its full fuel position. When the control rack 6 reaches full fuel position, its motion is arrested and the control tube 4 starts to rotate. Rotation of the control tube 4 is resisted by the governor springs which react on the rod 12. When the resistance to the tightening of this screw noticeably increases, indicating that the control rack 6 has been arrested by its having reached full fuel position the governor control is moved toward full fuel position and the adjusting screw 7 is loosened sufficiently to permit the governor control to reach full fuel position. The adjusting screw 8 is then tightened. The gage 16 is then mounted so that the prongs 21 rest on the horizontal face of the lip of the cylinder head and the prong 22 engages the vertical face of the lip and the movable anvil receives the pin 15 in the notches 31.

The set screw 39 is then loosened and the slide 34 carrying the indicating gage is moved along the bracket 32 until the feeler 36 contacts the movable anvil 29 and the pointer has made one complete revolution. This assures the removal of any slack from the gage. The set screw 39 is then tightened. The dial 40 is then rotated until the zero marking coincides with the pointer indication. When the governor control is then moved from full fuel position back to idle position the gage should register a deflection of ap-

proximately 0.003 inch if number one injector is properly set.

The manner of adjustment of number one injector prior to application of the gage as above described follows the usual present practice. Any errors indicated by the gage may be corrected by making such adjustments as are necessary not only to the control connector but also to the governor. Since these adjustments are not a part of this invention, they will not be elaborated upon.

After number one injector has been properly adjusted, the mechanic may proceed to adjust number two injector. The adjustment of the number one injector establishes a definite range through which the master control element may move as the governor control is moved from idle to full fuel position. The remaining connectors could be set in positions which would not affect this range, but which positions would be improper. The governor control is set in idle position. Tangent adjusting screw 7' is tightened moving connector 5' and its associated control rack 6' toward full fuel position. When the control rack 6' reaches its full fuel position, it can travel no further. Further tightening of the tangent adjusting screw 7' will result in the displacement of the control tube 4 which would change the gage reading. Over-tightening of screw 7' will cut down the range of motion through which the control tube can move and destroy the adjustment of the injector 2, i. e. the number one injector. In practice, therefore, screw 7' is tightened until the hand on the gage indicates that the control tube is starting to move. At this time tangent adjusting screw 8' is tightened. It makes no difference in what position the governor control is when this adjustment is made to number two injector, but it is ordinarily performed with the governor control in idle position. However, it is imperative that the pointer 37 start to move slightly as this assures that the control rack 6' has the same initial position as the control rack 6. As the governor control is again moved from idle to full fuel position the same deflection of approximately 0.003 inch should result. If the deflection is less than that amount, the tangent adjusting screw 7' is too tight. Both tangent adjusting screws 7' and 8' should be loosened, and 7' tightened again, being sure that the pointer 37 moves only very slightly.

When number two injector is properly adjusted the procedure is repeated on number three injector and so on for each successive injector in the engine.

It will be understood that while the gage readings for the idle and full fuel positions of the governor control are the critical readings for the purposes of the described embodiment, other critical readings and positions will suggest themselves to those skilled in the art when using the method in connection with other makes of engine.

I claim:

The method of coordinating the movement of the control racks of the fuel injectors of a multi-cylinder compression ignition engine of the type in which a single master control element actuates the racks, one for each injector, through an adjustable linkage whereby said rack and said control element may be moved relatively to each other which method comprises commencing with one of said control racks properly adjusted relatively to said element, motion of said control element and said adjusted rack being thus

limited at one of its extremes by arrest of said rack, and limited at its other extreme by arrest of said control element; mounting a direct reading gage between said element and a fixed part of the engine; setting said control element and the adjusted rack at one of said limits; adjusting the linkage associated with a second injector so as to move its associated control rack relatively to said element and toward its limiting position; discontinuing such movement of the rack when it is arrested, arrest of said rack being indicated by movement of the control element and the associated gage; setting the linkage being adjusted and the associated control rack at the point where its arrest occurs; and with the 15 gage still in place setting any remaining unadjusted control racks in the same manner as said second control rack.

HARRY AMOS JOHNSON.
